STACK PUSHER

Clarence M. Ellis, Lodi, Calif., assignor of one-third to J. E. Devine and one-third to James M. Prentice, both of Lodi, Calif.

Application May 8, 1944, Serial No. 534,679

5 Claims. (Cl. 254—114)

This invention relates to, and it is an object to provide, a device for pushing vertical stacks of produce boxes to desired positions without lifting such stacks from the floor; the device being especially useful in connection with the loading of stacked produce boxes in railroad refrigerator cars wherein the load comprises a plurality of stacks of boxes disposed in closely adjacent, symmetrical relation.

Another object of the invention is to provide a stack pusher, as above, which is so arranged that it may also be effectively used to vertically align the boxes of any given stack.

A further object is to provide a stack pusher which comprises a base including floor engaging teeth projecting downwardly therefrom adjacent the rear end, the forward end of said base being wheel supported, a foot actuated slide mounted on the base for longitudinal sliding movement, and a box stack engaging post upstanding from the slide at its forward end and beyond the corresponding end of the base.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of the stack pusher in operative position.

Figure 2 is an enlarged, fragmentary elevation, mainly in section, illustrating the working parts in locked position.

Figure 3 is a top plan view of the stack pusher.

Referring now more particularly to the characters of reference on the drawings, the stack pusher comprises a flat, elongated base 1 supported adjacent its forward end by transversely spaced floor engaging rollers 2. Adjacent its rear end the base is fitted with a pair of rearwardly and downwardly inclined flanges 3 which are rigid and relatively narrow; said flanges each being formed at the lower edge with a row of sharp, floor engaging teeth 4 which likewise project rearwardly and downwardly. Similar and adjacent teeth 5 are formed in the side flanges 6 of the base.

Adjacent but short of its forward end and on top the base 1 is fitted with a fixed, open-ended guide sleeve 7 which extends horizontally and lengthwise of said base. Such sleeve is here

shown as being rectangular in cross section and includes a top plate 8 and sides 9.

A slide 10, including upstanding side flanges 11, is engaged in slidable relation in sleeve 7 and normally projects out of the forward end of the latter; the projecting portion of said slide being formed with a pair of transversely spaced, rigid, upstanding ears 12 which normally extend to the front end of base 1, as shown in Fig. 2.

10 A vertical, box stack engaging post 13 is disposed at its lower end portion between the ears 12, and said post is pivoted in connection with said ears for swinging movement in a longitudinal vertical plane by means of a cross bolt 14. The bolt 14 passes through the post adjacent the upper ends of ears 12 and thus short of the lower end of the post which terminates adjacent the horizontal plane of the top of the base. As so mounted, the front or face of post 13 is disposed 15 slightly ahead of the forward end of base 1.

15 The post is provided at its upper end with laterally and oppositely projecting handles 15, and the post is normally locked against swinging motion by means of a spring pressed latch pin 20 slidably mounted on the back of the post; said pin 16 engaging at the lower end in a socket 17 in the top plate 8 of sleeve 7. At its upper end and adjacent handles 15, the pin 16 is formed with a lateral control finger 18. When the pin is engaged in socket 17, the slide 10 is held in retracted 25 position, as shown in Fig. 2.

25 A foot actuated, slide advancing device is employed, and such device comprises a lever unit 19 which is pivoted at its forward end on a cross rod 20 extending between upstanding ears 21 on the slide 10 adjacent the rear; the lever unit being inclined upwardly and rearwardly from said cross rod and at its upper end said lever unit is 30 fitted with a foot pedal 22. A link 23 is pivotally connected at one end to the lever unit 19 intermediate the ends of the latter, as at 24, and slopes rearwardly and downwardly therefrom to pivotal connection with the base adjacent its rear end, as at 25. A loaded tension spring 26 connects between the cross rod 20 on the slide and a rearward point on the base whereby such spring normally acts to retract the slide.

35 The above described stack pusher is used in the following manner:

40 To shift a stack S of boxes without lifting the stack from the floor, as for example in a railroad refrigerator car, the stack pusher is advanced on rollers 2 until the post 13 abuts against one side or one end of the stack. The operator then places 45 his foot on the pedal 22 and, after releasing pin 16

from socket 17, depresses said pedal. This causes the slide 10 and post 13 to advance relative to the base 1, as retraction of the latter is prevented by teeth 4 biting into the floor. Thus, as the slide and post are advanced, the stack of boxes is shifted in the desired direction.

If the stack is difficult to move in the above manner, a more forceful moving action can be obtained by swinging the post rearward at the top, which causes the lower end portion P of said post to swing forward in engagement with the lowermost box B of stack S. With the relatively great leverage thus obtained, the stack can be shifted.

The face of post 13 is formed with a vertically extending, full length, V notch 27, whereby the stack pusher can be engaged with a corner of a stack if desired to shift the stack diagonally.

The stack pusher may be used, too, as a means for vertically alining boxes of a stack by disposing the post adjacent a stack and then swinging the post slightly forwardly relative to a vertical position whereby to engage an out-of-line box and shift it back to correct position, as illustrated in dotted lines in Fig. 1.

The teeth 5 on side flanges 6 of base 1 are provided for the reason that in railroad refrigerator cars the floors are slotted, and thus if the transverse rows of teeth 4 rest over a slot, the teeth 5 become immediately effective.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A box stack pusher comprising a base adapted to be supported from a floor, means on the base to bite into the floor and prevent retrac-

tion of the base, a slide mounted on the base for movement lengthwise thereof, a member mounted on the slide for engagement with a stack of boxes, and means to advance the slide relative to the base; said slide including a pair of transversely spaced, upstanding ears adjacent the forward end of the base, and said stack engaging member being a post pivotally mounted between and upstanding from said ears.

10 5 2. A box stack pusher as in claim 1 in which the post is pivoted adjacent but short of its lower end in connection with said ears for swinging movement in a longitudinal vertical plane.

3. A box stack pusher comprising a base adapted to be supported from a floor, means on the base to bite into the floor and prevent retraction of the base, a guide sleeve mounted lengthwise on the base, a slide in and projecting forwardly from the sleeve, means to advance and retract the slide, an upstanding, vertically elongated post mounted on the slide forwardly of the sleeve, and a vertically movable latch pin mounted on the post at the back, said sleeve having a socket therein in position to receive the pin when the slide is retracted.

15 25 4. A stack pusher as in claim 3 in which the post is mounted on the slide for swinging movement in a longitudinal vertical plane.

5. A pusher for a plurality of boxes stacked in superimposed relation, such pusher comprising a base adapted to be supported from a floor, means on the base to engage the floor and prevent retraction of the base, a slide mounted on the base for horizontal movement lengthwise thereof, a foot operated means to forcefully move the slide along the base in a forward direction, the forward end of the slide when advanced extending some distance ahead of the base, a tension spring interposed between the slide and base and 30 35 40 functioning to retract the slide from forward position upon release of the slide advancing means, and an upstanding post on the slide at its forward end, such post being of a height to engage all the boxes of the stack and move them as a unit with the forward advancement of the slide.

CLARENCE M. ELLIS.
